UNITED STATES PATENT OFFICE.

JOHN F. O'CONNOR, OF CHICAGO, ILLINOIS, ASSIGNOR TO WILLIAM H. MINER, OF CHAZY, NEW YORK.

FRICITION SHOCK-ABSORBING MECHANISM.

1,357,801.

Specification of Letters Patent.

Patented Nov. 2, 1920.

Application filed April 3, 1919. Serial No. 287,174.

To all whom it may concern:

Be it known that I, JOHN F. O'CONNOR, a citizen of the United States, residing at Chicago, in the county of Cook and State of Illinois, have invented a certain new and useful Improvement in Friction Shock-Absorbing Mechanisms, of which the following is a full, clear, concise, and exact description, reference being had to the accompanying drawings, forming a part of this specification.

This invention relates to improvements in friction shock absorbing mechanisms.

One object of the invention is to provide a friction shock absorbing mechanism more particularly adapted for railway draft riggings and wherein the parts are compactly arranged.

More specifically, the object of the invention is to provide a friction gear for railway draft riggings so arranged that the same may go within a comparatively small space, approximately 18 $\frac{1}{2}$ ", and having all of the friction elements and springs confined entirely between the sills.

In the drawings forming a part of this specification, Figure 1 is a part elevational view, part longitudinal, vertical section of a portion of a railway draft rigging showing my improvements in connection therewith. Fig. 2 is a horizontal, sectional view taken substantially on the line 2-2 of Fig. 1. Fig. 3 is a vertical, transverse, sectional view taken substantially on the line 3-3 of Fig. 1. Fig. 4 is a view similar to Fig. 1 but illustrating a somewhat different embodiment of the invention. And Fig. 5 is a detail, perspective view of one of the friction shoes employed in the construction illustrated in Fig. 4.

Referring first to the construction illustrated in Figs. 1, 2 and 3, 10-10 denote channel-shaped draft sills, to the inner faces of which are secured front and rear stops 11-11 spaced 18 $\frac{1}{2}$ ", as illustrated in the drawings. The draw bar 12 is operatively associated with the shock absorbing mechanism proper by means of a yoke 13, and the parts are supported by a detachable saddle plate 14.

The improved shock absorbing mechanism, as shown, comprises four end friction wedges A—A arranged in pairs at each end, laterally or vertically movable friction shoes

B and C, a central friction plate D, and 55 twin springs E—E.

Each friction wedge A extends transversely substantially from sill to sill and is provided at its outer end with a vertical face as indicated at 15 adapted to be engaged by 60 a follower or equivalent shown in Fig. 1, the draw bar butt or the filler block in the yoke. Each block A is also provided with a wedge face 16 inclined toward the center line of the gear and also with a horizontal 65 friction face 17 parallel to the center line of the gear.

The friction shoes B and C extend longitudinally between the end wedges A—A. The shoe C is provided at its ends with 70 wedge faces 18—18 coöperable with the corresponding wedge faces 16 of the two lower wedges A—A as viewed in Fig. 1. The friction shoe B is provided at the ends thereof with wedge faces 19—19 coöperable with 75 the corresponding wedge faces 16 of the upper wedges A—A. The friction shoe B is provided with downwardly extended substantially annular flanges 20—20 which merge as indicated at 21—21 in Fig. 2, said 80 shoe B having also an integral wall 22 at the bottom of said flanges 20 so that, in effect, two cups or circular pockets are formed within which are received, centered and guided, the springs E—E. The lower friction shoe C is formed with a pocket or recess 23, indicated in Fig. 3, to receive the lower part of the spring receiving cups or pockets of the friction shoe B. Axially of each annular flange 20, the lower wall 22 of 90 the shoe B is perforated as indicated at 24 to accommodate a corresponding lug or boss 25 formed on the shoe C, as shown in Fig. 1. The shoe C is perforated to accommodate a pair of bolts 26 extending up through the 95 springs E and having heavy washers or followers 27 mounted thereon at the top and retained by suitable nuts 28.

The plate D has horizontal upper and lower friction faces as indicated at 29—29, 100 the same coöperating with the horizontal faces 17 of the four wedges A—A. The plate D is provided centrally thereof with an elongated opening 30 to snugly accommodate the spring receiving pockets of the 105 friction shoe B, as shown most clearly in Fig. 2. With this construction, it is evident that any longitudinal movement of the fric-

tion shoe B will be accompanied by a corresponding longitudinal movement of the plate D. In order to permit longitudinal movement of the shoe B with respect to the end wedges A—A, the latter are provided with circular recesses as indicated at 31—31, the same normally clearing the ends of the spring forming pockets of the shoe B as shown in Fig. 2.

- 10 In operation, upon inward movement of the draw bar, the rear set or pair of wedges A—A will be held stationary and as the front set of wedges A—A are forced relatively toward the rear set, the friction shoes 15 B and C will be forced apart vertically or in a direction at right angles to the axis of the gear. This separating movement of the shoes B and C will, of course, be opposed by the springs E which are compressed between the lower wall 22 of the shoe B and the spring washers 27—27. Obviously, friction will be generated between the wedges A—A and the shoes B and C during the movement just described. In addition, friction 25 will be generated between all of the wedges A—A and the plate D since there will be relatively horizontal movement between all of said wedges A and the plate D since the latter is governed entirely in its 30 longitudinal movements by the position of the friction shoe B.

With the arrangement described, it will be noted that all of the parts are contained within a relatively small space; the springs 35 are compressed in a direction at right angles to the line of movement of the draw bar but are confined entirely between the sills, thus avoiding the necessity of perforating the sills so as to permit mounting of the springs 40 outside of the latter; and all of the friction members can readily be manufactured in the form of ordinary castings, thus minimizing the initial cost of manufacture.

In the construction illustrated in Figs. 4 45 and 5, the arrangement of draft sills, stops, draw bar, yoke and saddle plate is the same as in Figs. 1, 2 and 3. The friction mechanism proper comprises the same general arrangement as that shown in the other figures except for small variations. The end wedges A'—A' have inclined wedge faces 116 and horizontal friction faces 117, the latter coöperating with corresponding upper and lower friction faces 129 on a central 50 plate D'. Two friction shoes are employed referenced B' and C', the same having end wedge faces 119—119 coöperable with the wedge faces 116. In the construction shown in Figs. 4 and 5, the shoes B' and C' are 55 counterparts, one of them being illustrated in Fig. 5. As there shown, it will be noted that the same is provided with a plurality of rectangular, integrally formed, spaced loops 40—40. The loops 40 extend laterally 60 from the main part of the corresponding

shoe B' or C' and said loops are adapted to be overlapped or interfitted when the shoes B' and C' are assembled so that said loops 40 form a substantially rectangular pocket within which is received the spring E', as 70 shown in Fig. 4. In order that the plate D' may be properly assembled with the shoes B' and C' after the latter have had their loops 40 interlaced and the spring E' placed therein, said plate D' is formed in two sections, half on each side of the center line of 75 the gear. This accounts for the showing of the plate D' in Fig. 4 in elevation instead of in section, the division between the two parts of the plate D corresponding to the 80 plane of the section. As will be understood, the two sections of the plate D' are fitted over the loops 40 of the shoes B' and C' so that the plate D' as a whole moves in unison longitudinally with the shoes B' and C'. It 85 is thought the operation will be understood from the previous description of the operation of the construction illustrated in Figs. 1, 2 and 3.

I claim:

1. In a friction draft rigging for railway cars, the combination with draft sills, a draw bar and yoke-acting means associated therewith, of shock absorbing mechanism operatively associated with the draw bar and yoke-acting means, said mechanism including a plurality of wedges at each end thereof and movable parallel to the axis of the draft rigging, central and lateral friction members frictionally engaging with said 100 end wedges and provided with coöperating means preventing relative longitudinal movement therebetween, said lateral friction members being relatively separable at right angles to the center line of the draft rigging, said central friction member and end wedges having coöperable friction faces extending parallel to the center line of the draft rigging, and spring means located entirely between the sills and within the yoke-acting means for resisting said separating movement of the lateral friction members.

2. In a railway draft rigging, the combination with draft sills, a draw bar and yoke-acting means, of a friction shock absorbing mechanism operatively associated with said draw bar and yoke-acting means, said mechanism including end wedges arranged to be actuated upon movement of the draw bar and yoke-acting means, central and side friction members frictionally engaging with said wedges and provided with coöperating means preventing relative longitudinal movement therebetween, said side friction members being relatively separable and at 110 right angles to the line of movement of said draw bar and yoke-acting means, the central friction member and said end wedges having rectilinear movement only parallel to the center line of the draft rigging, and spring 115

means located entirely between the sills and within the yoke-acting means for resisting the separating movements of said side friction members.

- 5 3. In a friction shock absorbing mechanism, the combination with a pair of wedges at each end of the mechanism, the wedges of each pair being spaced and provided with center friction faces extending parallel to 10 the center line of the mechanism and with inwardly inclined friction wedge faces at their inner ends; of side friction members having wedge-shaped ends coöperable with said inclined friction wedge faces of the 15 end wedges, said side friction members being separated upon relative approach of said end wedges; centrally disposed friction means having the end portions thereof provided with friction faces extending parallel 20 to the center line of the mechanism, said end portions being disposed between and coöperating with the parallel friction surfaces of the end wedges; and spring means for resisting relative separation of said side 25 friction members and carried therein and located between the end wedges.

4. In a draft rigging for railway cars, the combination with a draw bar and a yoke-acting means and draft sills, of a friction 30 shock absorbing mechanism associated with said draw bar and yoke-acting means, said mechanism including end sets of wedges, the wedges of each set being spaced and said wedges having movement only in lines par- 35 allel to the center line of the draft rigging and actuated by the draw bar and yoke-acting means, a central friction member having its ends interposed between said end wedges and frictionally coöperating there- 40 with, side friction members having wedge-shaped ends coöperable with the end wedges, the side members being separated upon relative approach of said end sets of wedges, and spring means for resisting separating 45 movement of said side friction members, said springs extending through the central friction member and compressible in a direc-

tion at right angles to the center line of the draft rigging.

5. In a friction shock absorbing mech- 50 anism, the combination with end wedges mov- able relatively toward each other; of central and side friction members frictionally en- gaging with said wedges, said side friction members being relatively separable and at 55 right angles to the line of relative move- ment of said end wedges, the center friction member and the wedges being restricted to relative rectilinear movement; and spring means resisting the separating movements 60 of said side friction members, the spring means being located intermediate the end wedges and carried within the side friction members.

6. In a friction shock absorbing mech- 65 anism, the combination with pairs of end wedges; of a central friction member coöper- able with said end wedges; side friction members coöperable with said end wedges, said central friction member being recessed 70 intermediate its ends, and a spring extend- ing transversely through said recess, said spring being compressed upon relative sepa- ration of said side members.

7. In a friction draft rigging, the combi- 75 nation with the draft sills, stop-acting means, draw bar and yoke-acting means, of end wedges arranged in pairs and movable parallel to the center line of the gear, a cen- tral friction member coöperable with said 80 wedges, side friction members also coöper- able with said wedges, said side and cen- tral friction members being movable in uni- son parallel to the center line of draft, and spring means located entirely between the 85 sills for resisting relative movement of said friction members.

In witness that I claim the foregoing I have hereunto subscribed my name this 14 day of Jan., 1919.

JOHN F. O'CONNOR.

Witness:

CARRIE GAILING.
